The ornamental design for a baby sleep support, as shown and described.

DESCRIPTION

FIG. 1 is a front view of the baby sleep support with strips of fabric hook and loop fastener;

FIG. 2 is a rear view of the baby sleep support of FIG. 1;

FIG. 3 is a perspective view of the baby sleep support of FIG. 1 when the ends of the baby sleep support are secured;

FIG. 4 is a top view of the baby sleep support of FIG. 1 when the ends of the baby sleep support are secured;
FIG. 5 is a top view of the baby sleep support of FIG. 1;
FIG. 6 is a bottom view of the baby sleep support of FIG. 1;
FIG. 7 is a front view of the baby sleep support with strips of fabric hook and loop fastener;
FIG. 8 is a rear view of the baby sleep support of FIG. 7;
FIG. 9 is a perspective view of the baby sleep support of FIG. 7 when the ends of the baby sleep support are secured;
FIG. 10 is a top view of the baby sleep support of FIG. 7 when the ends of the baby sleep support are secured;
FIG. 11 is a top view of the baby sleep support of FIG. 7;
FIG. 12 is a bottom view of the baby sleep support of FIG. 7;
FIG. 13 is a front view of a variant embodiment of the baby sleep support of FIG. 1;
FIG. 14 is a rear view of the variant embodiment of the baby sleep support of FIG. 13;
FIG. 15 is a perspective view of the baby sleep support of FIG. 13 when the ends of the baby sleep support are secured;
FIG. 16 is a front view of a variant embodiment of the baby sleep support of FIG. 1;
FIG. 17 is a rear view of a variant embodiment of the baby sleep support of FIG. 1;
FIG. 18 is a front view of a variant embodiment of the baby sleep support of FIG. 1 with a section of fabric hook and loop fastener;
FIG. 19 is a rear view of the variant embodiment of the baby sleep support of FIG. 18;
FIG. 20 is a front view of a variant embodiment of the baby sleep support of FIG. 1 with columns of button holes;

FIG. 21 is a rear view of the variant embodiment of the baby sleep support of FIG. 20 with a column of buttons;
FIG. 22 is a front view of a variant embodiment of the baby sleep support of FIG. 1 with columns of eyes;
FIG. 23 is a rear view of the variant embodiment of the baby sleep support of FIG. 22 with a column of hooks;
FIG. 24 is a front view of a variant embodiment of the baby sleep support of FIG. 1 with columns of half snaps;
FIG. 25 is a rear view of the variant embodiment of the baby sleep support of FIG. 24 with a column of mating half snaps;
FIG. 26 is a front view of a variant embodiment of the baby sleep support of FIG. 1;
FIG. 27 is a rear view of the variant embodiment of the baby sleep support of FIG. 26;
FIG. 28 is a front view of a variant embodiment of the baby sleep support of FIG. 1 with columns of tabs;
FIG. 29 is a rear view of the variant embodiment of the baby sleep support of FIG. 28 with a column of hoops;
FIG. 30 is a view of an environment for the baby sleep support to illustrate the use of the baby sleep support; and,
FIG. 31 is a view of an environment for the baby sleep support to illustrate the use of the baby sleep support.
The stippled or broken lines shown in variant embodiments of the design illustrate features that may be variant and do not form part of the design in such variant embodiments. The break lines shown in the drawings indicate that no particular length is claimed.
